UNITED STATES PATENT OFFICE.

FRANK R. LEWIS, OF RENO, NEVADA.

REVOLVER-HOLSTER.

981,292.

Specification of Letters Patent. Patented Jan. 10, 1911.

Application filed April 4, 1910. Serial No. 553,169.

To all whom it may concern:

Be it known that I, FRANK R. LEWIS, citizen of the United States, residing at Reno, in the county of Washoe and State of Nevada, have invented new and useful Improvements in Revolver-Holsters, of which the following is a specification.

This invention relates to holsters for firearms, and is especially designed for the use 10 of the police and other service required to carry a weapon.

The object of my invention is to so construct a revolver holster that it will permit 15 of the instantaneous withdrawal of the weapon in case of emergency, and which is light and convenient, and adapted to be worn under the coat, just under and a little 20 in front of the arm, supported by a sling or harness attachment which passes over both shoulders, crossing on the back, without showing in front when coat is worn; or the device may be worn as an ordinary belt holster.

The invention consists of the parts and 25 the construction and combination of parts as hereinafter more fully described and claimed, having reference to the accompanying drawings, in which:—

Figure 1 shows the device applied. Fig. 30 2 is a rear view of the applied device. Fig. 3 is a front elevation of the holster. Fig. 4 is a rear elevation. Fig. 5 is an end view.

The general form of my holster A is similar to that of an ordinary belt holster, 35 but instead of being stitched up along its longitudinal edge it is left open, or slit, as at 2, down to within about an inch of the muzzle, having a cap or stop 3 suitably secured in the tip or bottom of the holster, 40 so that a revolver B may be swung out of the holster by a quick side movement.

Around the larger portion of the holster, where the cylinder is adapted to rest, is suitably secured a pear-shaped spring or 45 clip 4 to close tightly and normally the lobes 6 of the holster over the revolver when it is in place in the holster. The ends of the clip 4 are retained in suitable 50 pockets 7 on each side of the holster to keep the spring-clasp in place, and which also prevents the ends from becoming caught in the garments or otherwise. The revolver or pistol is held in place by the spring-clasp 4 adjusted around the holster about over 55 the cylinder or heavy part of the weapon, allowing the revolver to be drawn by a

quick side, upward or downward movement, through the slit or open holster. Secured to and extending the length of one side of the holster A is a strap 8 suitably slotted, 60 as at 9, to receive a belt C, or to be buttoned to the apparel of the wearer.

The holster is adapted to be carried on a special sling or harness, as follows: Secured to the holster A are upper and lower rings 65 10, 11, adapted to receive the respective ends of a pair of straps 14, 15, which latter cross in the back and pass over both shoulders without showing in front when a coat is worn. The strap 15 of the harness is fastened on the right side, Fig. 1, to the belt C, or to a suspender button by means of the cast-off 18. The other end of the strap or web 15 is brought over the right shoulder from in front, and down across the back and 75 under the left arm and attached to the lower ring 11 in the holster. The other strap 14 being attached to the cast-off 18 at 17 under the right arm, is brought up across the back and over the left shoulder and 80 down the front and attached to the upper ring 10. The belt is then passed through one of the belt straps in the holster, or by means of one of the button holes 9 in the belt straps on the holster is held in the position 85 desired.

The holster may be worn on the belt as any ordinary holster. In such case the belt strap on the holster should be placed behind a belt strap on the trousers, or buttoned to 90 the trousers to hold against the side pull. When worn on the belt, the revolver may be drawn by the side or downward movement, as described above, or in the old fashioned way.

The application of the device is as follows: Assuming that the straps 14, 15 have been properly secured to their respective rings 10, 11 on the holster A, the user passes his left arm through the loops formed by 100 the harness, draws the same over his back, and connects the cast-off 18 to the belt, or to a button, as shown at 19. This brings the holster to a vertical position a little in front of his left side and within easy reach 105 of his right hand, so that he has simply to grasp the handle or butt of the revolver, and instead of lifting it from the holster he has only to jerk it out with a swing in the direction desired, thus the drawing and 110 pointing of the weapon are accomplished with one and the same swinging movement.

The revolver can be readily replaced into the holster with the one hand with which it is drawn and without any necessary aid from the other hand.

5 Having thus described my invention, what I claim and desire to secure by Letters Patent is:—

1. An improved holster, said holster being open at the front and at one side, and having external means adapted to compress the sides to hold the side opening thereof normally closed, said means consisting of a single exterior curved spring extending around the outside of the holster and pockets on each side of the holster near the open side adapted to receive the ends of the

spring, and means for supporting the holster from the person.

2. The combination with a holster, of means for supporting the same from the person, said means consisting of a strap extending lengthwise of the holster having lengthwise extending slots, a ring at one end of the strap, and a second ring on the holster for attaching said holster to the person. 20 25

In testimony whereof I have hereunto set my hand in the presence of two subscribing witnesses.

FRANK R. LEWIS.
